DESCRIPTION

FIG. 1 is a perspective top view of a socket and heat sink unit for use with a removable LED light module showing my new design;

FIG. 2 is a perspective bottom view thereof;

FIG. 3 is a side view thereof;

FIG. 4 is another side view thereof, rotated 90 degrees from the view in FIG. 3;

FIG. 5 is another side view thereof, rotated 90 degrees from the view in FIG. 4;

FIG. 6 is another side view thereof, rotated 90 degrees from the view in FIG. 5;

FIG. 7 is a top view thereof; and,

FIG. 8 is a bottom view thereof.

The broken lines show unclaimed subject matter only and form no part of the claimed design.
